UNITED STATES PATENT OFFICE

PER K. FROLICH, OF CAMBRIDGE, MASSACHUSETTS, ASSIGNOR TO STANDARD OIL DEVELOPMENT COMPANY, A CORPORATION OF DELAWARE

PROCESS FOR THE TREATING OF HYDROCARBON MATERIALS

Application filed October 14, 1927. Serial No. 226,076.

The present invention relates to the art of treating hydrocarbon materials to form valuable liquid products and more specifically to a process for oxidizing hydrocarbons with air to form substantial yields of alcohols, aldehydes, acids and other oxygen-containing compounds. My process and the apparatus for carrying out the process will be fully understood from the following description and the drawing, which illustrates one form of apparatus suitable for that purpose.

The drawing is a semi-diagrammatic view in elevation of an apparatus constructed according to my invention and illustrates the flow of materials through the apparatus.

In a previous application, Serial No. 190,728, filed May 12, 1927, by the present inventor and another, a process for the direct oxidation of the lower boiling hydrocarbons with oxygen or oxygen-containing gases to form alcohols, acids, aldehydes, and other oxygen-containing compounds, was disclosed. My present invention relates specifically to an improved method of oxidizing hydrocarbons with air or other oxidizing gases containing diluent gas such as nitrogen, carbon monoxide, or carbon dioxide.

The use of air for the oxidation of hydrocarbons is economically advantageous because of its availability. It is also highly advantageous to recycle the unoxidized hydrocarbons through a reaction zone if one is to obtain large yields. My present invention comprises a method for economically carrying out the oxidation with air as the oxygen-containing gas.

Referring to the drawing, the reference character 1 designates a high pressure source of hydrocarbons which may be normally either liquid or gas, a single pure compound, or a hydrocarbon-containing mixture. This raw material, which will hereafter be termed hydrocarbon, is fed by a pipe 2 to a manifold 3 and then to a plurality of coils *a*, *b*, *c*, and *d*, which are carefully distributed throughout

the interior of a reactor 4 and in which the hydrocarbon is preheated. The reactor may be of any suitable design but is preferably a heavy steel shell adapted to withstand pressures in excess of 3,000 lbs. per square inch and a temperature of 600° C. or higher. The reactor is suitably lagged and may be fitted with other heat exchanging coils in addition to *a*, *b*, *c*, and *d*, but which have not been shown on the drawing for sake of simplicity. The body of the reactor may be otherwise empty or it may be partially filled with catalytic material, the nature of which was disclosed in application Serial No. 190,728. The hydrocarbon feed is distributed throughout the coils *a*, *b*, *c*, and *d* so as to absorb the heat evolved by oxidation and to maintain all parts of the reactor at approximately the same temperature, which is predetermined and called the reactor temperature. Part of the hydrocarbon is passed through a line E to a heat exchanger F and is there preheated by the reaction products from the reactor as will be described below, and a part of the hydrocarbon may be by-passed through line E'.

The preheated hydrocarbon passes to a manifold 5 and is thence conducted to a coil 6, wherein the hydrocarbon is heated to a temperature somewhat below that of the reactor and is then discharged into a mixing pipe 7. A by-pass line 6^a is provided so that all or part of the hydrocarbon may be shunted around the coil 6 after the reactor has reached its proper temperature. Air is compressed by a suitable compressor 8 and is also discharged into mixing pipe 7, wherein it is thoroughly mixed with the hydrocarbon. The mixture is then discharged into the reactor 4 and the heat of reaction immediately raises the temperature to the predetermined degree. If desired, part of the air may flow through pipe 9 and enter the reactor by a plurality of branch pipes *a'*, *b'*, and *c'*, in regulated quantities.

The mixture discharged from the reactor is cooled in exchanger F and a cooler 10 is then discharged through a reduction valve 11 into the intermediate portion of a rectifying column 12, or any apparatus commonly used to separate liquid and vapor. The column may be of any preferred design but bellcap plate columns are satisfactory. The column may be fitted with a cooling coil 13 in the upper portion, and a heating coil 14 at the base, which may be an open steam coil, if desired. Nitrogen and other permanent gases escape from the top of column 12 by line 15 and are conducted to the base of a gas scrubbing tower 16 into the lower part of which the gas is discharged through a spray pipe 17. A suitable solvent is admitted to the upper part of tower 16 through a spray pipe 18 and in passing downwards extracts any normally liquid oxidation products and valuable gaseous oxidation products, such as formaldehyde, which may have escaped from column 12 with the permanent gases. The solvent carrying the extracted material then flows by line 19 to a tank 20. Permanent gases leave tower 16 by line 21 which is fitted with valve 22 to hold pressure on the system. The gas may be expanded to furnish work for compressing air, as will be readily understood.

30 The liquid flowing from the base of column 12 comprises liquid oxidation products and unoxidized liquid hydrocarbon and is conducted to a liquid scrubbing system 24, which is shown as a column with bubble cap plates.

35 The hydrocarbon together with the oxidized products, is admitted to the base of the column 24 by spray pipe 25 and a suitable solvent, which has a specific gravity greater than the hydrocarbon, is admitted by spray pipe 26 at the top of column 24. The solvent makes its way to the base of the column, extracting the oxidation products, and is discharged by line 27 to the storage tank 20 or to separate storage by line 28.

40 45 In the drawing a system using the same solvent for towers 16 and 24 is illustrated and a pump 29 is used to circulate the solvent through the towers by circulation line 30 but as will be readily understood, the recovery systems for the two towers may be separate and different solvents may be used. I prefer to use the same solvent for both towers and to withdraw the rich solvent from tank 20 by line 31 to a separation system (not shown), which may consist of rectifying stills. Fresh or stripped solvent may be admitted by line 32.

50 Unoxidized hydrocarbon rises in column 24 and is forced by pump 33 through line 34 to a tower 35 into which it is fed through spray pipe 36. An alkaline solution, for example caustic soda, is circulated through this tower by pump 37 and line 38 to dissolve the carbon dioxide from the unoxidized hydrocarbon. The solution is withdrawn at the

base of tower 35 into a tank 39. Spent soda may be withdrawn by pipe 40 and fresh soda introduced by 41. The unoxidized hydrocarbon, freed of carbon dioxide, is withdrawn from the top of tower 35 and conducted back to tank 1 by pump 42 and line 43 for recirculation through the apparatus. This purification is desirable if ethane or methane is recirculated but can be dispensed with if only hydrocarbon heavier than ethane is recirculated since the carbon dioxide under these conditions can be drawn off at line 21 with nitrogen, as will be understood.

In the operation of my process, the hydrocarbon is under a pressure in excess of 1,000 lbs. per square inch and preferably between 1,500 and 3,500 lbs. per square inch. Air is fed at approximately equal pressure and the reactor is maintained under full or slightly lower pressure. The temperature of the reactor is preferably between 350 and 600° C., depending on the nature of the hydrocarbon and the specific catalyst used, as is fully discussed in the earlier application, Serial No. 190,728. The temperature of the gases entering the reactor can be regulated as desired by suitable adjustment of the apparatus described above, and the temperature within the reactor may be carefully regulated, not only by the coils a, b, c, and d, but also by adjustment of the proportion of air to hydrocarbon.

In starting up the process, it is advisable to circulate only hydrocarbon until temperature is raised and then to introduce air to build up the concentration of oxygen to the desired value. As a maximum, I may use one atom of oxygen per mol of hydrocarbon in the feed mixture and I preferably operate with a lower proportion of oxygen. The percent of oxygen in the feed is often below 10% and sometimes below 5%, since lower percentages appear to cause less waste by formation of CO and CO₂ and any danger of explosion by gas pockets is diminished, as will be understood.

As described in application, Serial No. 190,728, the rate of flow of the material through the reactor is of importance. The rate of flow is expressed by two methods. The "space velocity" is conveniently calculated and expressed in the units, "litres of gas, at standard conditions of temperature and pressure, per hour, per cubic centimeter of free reactor volume" and this rate should not be below 4.0. "Surface velocity" is likewise expressed at "litres of gas at standard conditions of temperature and pressure, per hour, per square centimeter of superficial catalytic surface." On this basis the surface velocity should be above .20 litres per hour per square centimeter. Preferably the rate of flow should be considerably higher. I have increased the "space velocity" about 80 litres per hour per cubic centimeter of reactor volume and "surface velocity" above 125 litres per hour per square centimeter.

7.90 litres per hour per square centimeter of superficial catalytic surface, and such velocities are desirable.

For separation of the diluent gas, the oxidized and unoxidized hydrocarbon I prefer to first use a rectifying tower as illustrated by 12 in the drawing. In this tower the nitrogen, may be easily separated from the normally liquid oxidation products and unoxidized hydrocarbon which is to be recycled. Pressure and temperature conditions in tower 12 vary somewhat with the nature of the hydrocarbon, but in general pressure and temperature should be so related that coil 13 will condense the lightest hydrocarbon which is to be recycled through the reactor, and temperature at coil 14 should be sufficiently high to boil the liquid under the prevailing pressure, as is necessary in any rectification system. Pressure below the critical pressure of the hydrocarbons used is maintained, and in general I prefer to maintain pressure as high as possible. I contemplate operating pressures up to 50 or 60 atmospheres with a temperature preferably below atmospheric at the top of column 12. At the base of the column temperature may be from about -100° C. to $+200^{\circ}$ C. If methane is to be recycled a refrigerant capable of producing a very low temperature must be used in coil 13 as will be understood. While I prefer to use a rectifying column such as tower 12, I might alternatively use a drum or the like for separation of gas and liquid and with such equipment a pressure above 60 atmospheres may be used. While I prefer to make a complete separation of nitrogen from the hydrocarbon and to recover all hydrocarbon from nitrogen it may be economical not to attempt to obtain complete separation since to do so would require very low temperatures as will be apparent.

For the solvent in towers 16 and 24 I prefer to use a solvent heavier than the hydrocarbons and immiscible therewith. I contemplate the use of substances containing an hydroxyl group such as water, glycerine, ethylene glycol, or methanol, or mixtures of these with each other or other substances. A solvent lighter than the hydrocarbon might also be used and in this case the hydrocarbon would be added at the top of the column, as will be understood.

As an illustration of the operation of my process, the following example is given of the oxidation of butane with air. A mixture of substantially pure butane and air was passed through a reactor partially filled with nickel wire catalyst. The oxygen concentration in the mixture was 4.9%, pressure 2400 lbs. per square inch and temperature approximately 430° C. "Space" velocity was 83.8 and "surface" velocity 7.95, both in the units above defined. The yield of liquid was 18 cubic centimeters for each 100 litres of butane gas by a

single passage through the reactor, and about 55.1% of the oxygen went to normally liquid organic oxidation products. The liquid on fractional distillation showed the following composition:

Boiling range:

Boiling range:	Up to 53° C. 50% acetaldehyde and 50% propionaldehyde (approx.)	3%	70
53-60	acetone	2	75
60-70	methanol	6	
70-78	95% ethanol, 5% water	16	
78-89	78% propanol, 22% water	31	
89-96	63% butanol, 37% water	5	
96-up	acetic acid, propyl acetate and water	37	

Chemical analyses of the liquid products gave the following results:

Acetic acid, % by volume	18.1	85
Propyl acetate, % by volume	6.0	

My process may be used for the oxidation of various hydrocarbons such as ethane, propane, butane, pentane, and the like. Methane and/or higher boiling hydrocarbons or mixtures thereof may also be present, but it is especially adapted for those hydrocarbons individually named either in a pure state or in artificial mixtures or natural mixtures such as will occur in natural gas or coal gas or refinery gas or in the lighter lower boiling distillates or condensates such as casinghead gasoline or natural gas gasoline and the like. My process is not to be limited by any theory of the mechanism of the process or by any illustrative example, but only by the attached claims, in which I wish to claim all novelty inherent in my invention.

I claim:

1. In a continuous process for obtaining normally liquid oxygen-containing products from hydrocarbons comprising low boiling and normally gaseous hydrocarbons, the step of bringing together said hydrocarbons and air under pressure in excess of 1,000 lbs. per square inch in a reaction zone, maintaining said zone at a predetermined temperature between 350 and 700° C. by circulation of a stream of fresh hydrocarbon therethrough in heat interchanging relation to the reacting materials, separating the normally liquid oxygen-containing products from the resulting mixture, separating the hydrocarbon and returning it to process.

2. In a process for obtaining liquid oxygen-containing products from readily liquefiable hydrocarbon material by direct oxidation with a gas containing free oxygen and a diluent, the steps of bringing such materials together under pressure in excess of 1,000 pounds per square inch and at temperatures between 350 and 600° C., cooling the hot gases under superatmospheric pressure to a temperature at which the liquid oxygen-contain-

ing products, together with hydrocarbon material, are obtained in liquid phase, and the diluent is obtained substantially entirely in the gaseous phase, separating the liquid from the gas, separating the hydrocarbon material from the oxygen-containing products and returning the hydrocarbon material to the process.

3. In a process for obtaining liquid oxygen-containing products from readily liquefiable paraffinic hydrocarbons by direct oxidation with air, the steps of bringing such materials together under pressures in excess of 1,000 pounds per square inch and at temperatures between 350 and 600° C., cooling the hot gases under substantially the same pressure to a temperature at which a liquid phase comprising normally liquid oxygen-containing products and hydrocarbons and a vapor phase comprising substantially permanent gases are obtained, separating the liquid from the gas, separating the unreacted hydrocarbon from the liquid and returning the hydrocarbons to the oxidation.

25 4. Process according to claim 3 in which the oxidation is carried out under pressure between 1500 and 3500 pounds per square inch in the presence of a catalytic material.

5. An improved process for obtaining oxidation products rich in alcohols from readily condensable hydrocarbons which comprises passing such hydrocarbons with air through an oxidation zone maintained at temperatures between 350 and 600° C. and under pressures in excess of 1,000 pounds per square inch, cooling the effluent mixture under superatmospheric pressure whereby a condensate is produced, separating the condensate from the gases, extracting the oxidation products from the condensate by means of a suitable liquid solvent for such oxidation products, and recycling the unoxidized hydrocarbons to the oxidation.
